UNITED STATES PATENT OFFICE.

BERNARD S. DOYLE AND ALFRED S. PATTON, OF LEBAM, WASHINGTON.

WATER-MOTOR.

1,036,587.

Specification of Letters Patent. Patented Aug. 27, 1912.

Application filed December 6, 1911. Serial No. 664,264.

To all whom it may concern:

Be it known that we, BERNARD S. DOYLE and ALFRED S. PATTON, citizens of the United States, residing at Lebam, in the county of Pacific and State of Washington, have invented certain new and useful Improvements in Water-Motors, of which the following is a specification.

Our invention has for its primary object the provision of novel mechanism of the above type capable of being operated by a comparatively slight fall of water.

A further object resides in the provision of a construction wherein pump mechanism is connected to be operated in a novel manner.

Other objects will be set forth as our description progresses and those features of construction, arrangements and combinations of parts on which we desire protection, succinctly defined in our annexed claims.

Referring to the accompanying drawings, wherein like numerals of reference indicate like parts throughout: Figure 1 is a vertical section taken through the working chamber. Fig. 2 is a cross-sectional view taken on line 2—2 of Fig. 1, and Fig. 3 is a fragmentary plan, illustrating more particularly one of the working chambers and its valved connection with the water supply flume.

Referring to the drawings by numerals of reference, 1 indicates vertical chambers in which pistons 2 are mounted to reciprocate, the latter having their stems 2' slidably engaged in suitable guides 3 and pivotally connected by links 4 with the adjacent end portions of a walking beam 5, fulcrumed at 6 on a suitable standard 7.

Reference numeral 8 indicates a reservoir or well into which the lower end portions of chambers 1 open, the points of communication being below the overflow ports 9 of said reservoir, whereby pistons 2 after passing outlet ports 1', will have the remaining portions of their downward strokes cushioned by the air confined between the piston and the body of water in the reservoir or well 8.

Reference numeral 10 indicates a delivery head connected to receive water, as from a flume 11 and communicating with suitable intake ports 1'', provided in the upper end portions of chambers 1, through the intermediary of passages 12, controlled by suitable valves, as 13. Valves 13 are conveniently shown as being of the sliding type, the same being connected by a stem 14 for

simultaneous movement of one to its closed position and the other to its open position, as more clearly shown in Fig. 1. As now considered, valves 13 operate through openings 13' provided in the inner side walls of passages 12 and during their withdrawal, or movement to an open position, are engaged or received in guides 15, provided on the adjacent wall of head 10.

In the present embodiment of our invention, provision is made for the utilization of the power generated to lift water, as for irrigation purposes. This mechanism comprises pumps 16, fixed to the upper wall of reservoir 8 and having their valved lower end portions projecting into the latter.

Reference numeral 17 indicates a delivery pipe which is connected by the valved branches 18 with the chambers of pumps 16.

The pump pistons 19, which are of the valved type, have their stems 19' connected by links 20 with walking beam 5 on opposite sides of fulcrum 6.

Reference numeral 21 indicates a valve shifting arm, the same being pivoted at 22 to standard 7 and having its upper end portion connected as at 23 with stem 14. The lower end portion of arm 21 is provided with integral angular extensions 24 lying in the path of respective strike lugs 25, adjustably secured as by set screws 26 to the pump piston stems 19'. By this construction, during upward movement of a piston which effects a discharge of water into delivery pipe 17, arm 21 will be swung to shift valves 13. This shifting of the valves occurs preferably as a piston 2 moves a little below the upper end portion of its related discharge port 1' so that simultaneously with the discharging of water from one working cylinder 1, water is discharged from head 10 into the other cylinder.

Delivery head 10 is shown as being supported on uprights 30. It however, can be supported in any desired manner. Further the particular construction of reservoir or well 8 is immaterial, it primarily being our intention in this connection to provide a chamber wherein the fluid is maintained for pumps 16.

The supplying of reservoir or well 8 from chambers 1, as hereinbefore set forth, renders the apparatus more economical with respect to the use of the water as is apparent.

In the operation of our invention pistons

2 move downwardly, in an alternate manner, under the weight of the water in the upper portions of chambers 1, the imposed weight increasing during downward movement of the piston until the piston reaches or approximately reaches the outlet port 1' of the cylinder, at which time the valve 13 of the related inlet port 1" will be closed, as hereinbefore set forth.

10 Having thus described our invention, what we claim as new, and desire to secure by Letters Patent of the United States of America, is:—

15 1. In apparatus of the character described, a delivery head, spaced vertically arranged chambers provided in their upper end portions with inlet ports connected with said delivery head, slide valves controlling the inlet ports of said chambers, means connecting said valves for simultaneous movement, said chambers being provided in their lower end portions with outlet ports, pistons slidably fitting in said chambers, a walking beam, means connecting said pistons each 20 with a respective end portion of said walking beam, a pair of pumps having reciprocating pistons, link connections between the stems of the pistons of said pumps and said walking beam, pivotally supported valve 25 actuating means connected with said first 30

named means, and abutment means movable with said stems for swinging said valve actuating means.

2. In apparatus of the character described, spaced vertically arranged chambers, provided in their upper portions with inlet ports and in their lower portions with outlet ports, a reservoir into which the lower ends of said chambers open, the outlet ports being disposed above the lower ends of said chambers and connected to discharge into said reservoir, pistons supported in said cylinders for movement past the said outlet ports thereof, valves for the inlet ports of said chambers, a walking beam, means pivotally supporting said walking beam, means connecting each of said pistons with a respective end portion of said walking beam for movement therewith, and means operated by and during movement of said walking beam for operating said valves alternately to an open position. 35 40 45 50

In testimony whereof we affix our signatures in presence of two witnesses.

BERNARD S. DOYLE.
ALFRED S. PATTON.
